US00D695404S

(12) **United States Design Patent**
Horning et al.

(10) **Patent No.:** US D695,404 S
(45) **Date of Patent:** ** Dec. 10, 2013

(54) **BIOPSY DEVICE**

(75) Inventors: **Julie A. Horning**, Loveland, OH (US);
Kathryn M. Dodd, Cincinnati, OH (US); **John A. Hibner**, Mason, OH (US); **Emmanuel V. Tanghal**, Mason, OH (US)

(73) Assignee: **Devicor Medical Products, Inc.**, Cincinnati, OH (US)

(**) Term: **14 Years**

(21) Appl. No.: **29/422,286**

(22) Filed: **May 18, 2012**

Related U.S. Application Data

(63) Continuation-in-part of application No. 29/418,015, filed on Apr. 11, 2012, and a continuation-in-part of application No. 13/226,660, filed on Sep. 7, 2011.

(57) **CLAIM**

The ornamental design for a biopsy device, as shown and described.

DESCRIPTION

FIG. 1 is a top perspective view of a biopsy device, showing our new design;

FIG. 2 is a bottom perspective view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The needle assembly, holster assembly, and probe body assembly shown in broken lines are unclaimed subject matter and form no part of the claimed design.

1 Claim, 5 Drawing Sheets
